UNITED STATES PATENT OFFICE.

HANS P. SCHEEL, OF TENINO, WASHINGTON.

GAS-COLLECTING ATTACHMENT FOR COKE-OVENs.

1,240,494.

Specification of Letters Patent. Patented Sept. 18, 1917.

Application filed January 17, 1917. Serial No. 142,924.

To all whom it may concern:

Be it known that I, HANS P. SCHEEL, a citizen of the United States, residing at Tenino, in the county of Thurston and State of Washington, have invented a new and useful Gas-Collecting Attachment for Coke-Ovens, of which the following is a specification.

This invention relates to an attachment for coke ovens whereby the gaseous products of destructive distillation which have heretofore usually been wasted, can be collected and conveyed to separating apparatus for the recovery of by-products or can be used for power or other purposes.

Heretofore, when it has been desired to save and utilize gases generated in coke ovens, it has been practically necessary to remodel the ovens or to build special ovens along original lines. Because of the expense entailed, comparatively few ovens of this nature have been erected and consequently, a vast amount of gas has been wasted whereas it might have been utilized in the production of hydrocarbon by-products, in the production of power, and for illumination purposes.

One of the objects of the present invention is to provide an attachment which can be readily combined with an ordinary bee-hive oven without changing the construction of the oven and without interfering in any way with the ordinary operation thereof.

A further object is to provide an attachment which will collect all of the gases generated within the oven and conduct them to any point desired, the said collecting means operating as a safety valve whereby the generated gas is free to escape if generated too rapidly and likely to cause an explosion within the oven.

A further object is to provide an attachment which can be easily shifted to permit the oven to be filled in the ordinary manner, the said attachment when in active position serving as a positive means to prevent leakage of gas from the oven.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made

within the scope of what is claimed, without departing from the spirit of the invention.

In the accompanying drawings the preferred form of the invention has been shown.

In said drawings:

Figure 1 is a view partly in elevation and partly in section of the attachment in position on a coke oven, a portion of the oven being shown.

Fig. 2 is an enlarged section on line 2—2 Fig. 1.

Fig. 3 is a section on line 3—3 Fig. 2. 70

Fig. 4 is an enlarged section through a portion of the base ring or seat of the attachment and a portion of the hood engaging the same.

Referring to the figures by characters of reference 1 designates a portion of a coke oven which can be of the bee-hive type having a feed opening 2 in the top thereof through which the coal may be discharged into the oven from a car or elevator or in any other well known manner. The attachment constituting the present invention and by means of which the generated gases can be withdrawn from the oven, includes a base ring or seat 3 adapted to be inserted into the opening 2 so as to fit snugly against the wall thereof, this ring having an annular flange 4 in the upper face of which is formed a circular groove 5. This groove is designed to receive the lower edge portion 90 of a hood 6 which is reduced as at 7 and merges into a stack or outlet flue 8. This outlet flue is provided, near its upper end, with an annular enlargement 9 forming a shoulder 10 and the upper extremity of the flue 95 is flared as at 11 thus to constitute a seat for a packing ring 12 of asbestos or other suitable heat resisting material. The shoulder 10 also constitutes a seat for a packing ring 13 of asbestos or the like. The enlargement 100 9 is engaged by steel cables 14 or the like mounted on guide sheaves 15 which, in turn, are supported by brackets 16 outstanding from a conducting pipe 17 which is fixedly mounted. These cables are provided with counter balances 18 which can be detachably secured thereto. The pipe 17 projects into the flue 8 for a short distance and slidably engages the packing ring 12. A retaining ring 19 is slidably mounted on the pipe 17 110 and has a depending flange 20 designed normally to rest upon the packing ring 13.

Ring 19 also has a tapered portion 21 adapted to engage the packing ring 12 and to bind it on the flared end or shoulder 11 so as to press said ring 12 against the pipe 17, thereby to seal the joint between said pipe and the flue 8. Lugs or projections 22 are formed on or secured to the ring 19 and by means thereof said ring can be shifted upwardly along the pipe 17 thus to permit 10 convenient renewal of the packing rings.

The pipe 17 is adapted to be supported in any suitable manner above the opening 2, sufficient clearance space being left to allow cars to pass thereunder to deliver coal to 15 the oven or to allow for the discharge of coal from suitable elevators. If desired this pipe 17 can open into a main from which a number of pipes depend above a series or battery of ovens. Ring 3 can be 20 placed in the opening 2 without seriously interfering with the operation of the oven and after it has thus been positioned and the pipe 17 has been mounted above the opening, the flue 8 can be lowered so as to cause 25 the lower edge of the hood 6 to rest snugly in the groove 5. Clay such as indicated at 23 can then be placed in the groove 5 and along the outer side of the hood so as to seal the joint and the weights 18 can be detached 30 from the cables 14. The apparatus is now in condition for use and as the coal in the oven is heated the generated gases will flow upwardly through the opening 2 and the hood 7 into flue 8 and pipe 17 and can 35 then be conducted to the point of use. Should the generation of the gases be too rapid, the excessive pressure of the gases against the hood 7 will cause the hood to lift off of the ring 3, flue 8, at this time, 40 sliding upwardly along the pipe 17. Thus the surplus pressure will be released and injury to the oven will be prevented. When it is desired to lift the attachment so as to allow the oven to be charged, the weights 45 18 are attached to the cables and the hood 7 can then be thrust upwardly until sufficient clearance has been provided to allow the cars or other supplying means to pass into position over the opening 2. Obviously 50 when the flue 8 is raised the ring 19 and the packing 12 and 13 will shift therewith along the pipe 17. The packing can be renewed whenever desired simply by lifting the ring 19 relative to the flue 8, whereupon 55 new packing rings can be placed in position and when the ring 19 is released it will gravitate onto said rings and compress them so as to completely seal the joint.

By providing a gas collecting apparatus 60 such as described, the gases which are generated in bee-hive ovens and ovens of other construction and which gases have heretofore been wasted, can be collected and utilized at slight additional cost over and above 65 the cost of the ovens. Furthermore, an at-

tachment such as described is advantageous because its installation does not necessitate the shutting down of the oven for any considerable length of time nor does it interfere with the ordinary means employed for 70 charging the oven.

As an additional means for preventing leakage of gas at the joint between the pipe and the slidable flue, the ring 19 may be flared at its upper end as shown at 19', thus 75 to receive an additional packing.

It will be noted that the groove 5 in which the lower edge of the hood 6 rests is of considerable width as compared with the thickness of the hood. This is provided 80 in order that the hood may be free to expand and contract while seated in the groove.

What is claimed is:—

1. The combination with a coke oven having a feed opening in the top thereof, of means for conducting gases from the oven, said means including a gas conducting pipe supported above and in line with the opening, and a hood removably mounted on the 90 oven and around the opening and below and communicating with the pipe, said pipe and hood being concentric with the axis of the opening.

2. The combination with a coke oven having a feed opening in the top thereof, of gas collecting means including a gas conducting pipe supported above and in line with the opening, a base member upon the oven and surrounding the opening, 100 and a flue supported by said base member and below and communicating with the pipe, said flue being movably mounted, said pipe and flue being concentric with the axis of the opening.

3. The combination with a coke oven having a feed opening in the top thereof, of means for collecting gas from the opening, including a gas conducting pipe overhanging the opening, a base member upon the 110 oven and surrounding the opening, and a flue slidably mounted on said pipe and normally seated at its lower end upon said base member, said flue and pipe being concentric with the axis of the opening.

4. The combination with a coke oven having a feed opening in the top thereof, of means for collecting gas from the opening, including a gas conducting pipe overhanging the opening, a base member upon the 120 oven and surrounding the opening, a flue slidably mounted on said pipe and normally seated at its lower end upon said base member, and means for sealing the joint between the pipe and flue, said flue and pipe being 125 concentric with the axis of the opening.

5. The combination with a coke oven having a feed opening in the top thereof, of means for collecting gas generated in the oven, said means including a gas conducting 130

- pipe supported above the opening, a flue slidably mounted on said pipe and normally supported at its lower end by the oven, the lower end of said flue surrounding the opening, said flue having an inwardly extending portion for receiving pressure from generated gases.
6. The combination with a coke oven having a feed opening in the top thereof, of means for collecting gas generated in the oven, said means including a gas conducting pipe supported above the opening, a flue slidably mounted on said pipe and normally supported at its lower end by the oven, the lower end of said flue surrounding the opening, said flue having an inwardly extending portion for receiving pressure from generated gases, and means for sealing the joint between the oven and the lower end of the flue.
7. The combination with a coke oven having a feed opening in the top thereof, of means for collecting generated gases, including a gas conducting pipe supported above the opening, a flue slidably mounted on said pipe and having an enlargement at its lower end surrounding the opening and resting on the oven, and means for sealing the joint between said enlarged end of the flue and the oven.
8. The combination with a coke oven having a feed opening in the top thereof, of means for collecting generated gases, including a gas conducting pipe supported above the opening, a flue slidably mounted on said pipe and having an enlargement at its lower end surrounding the opening and resting on the oven, means for sealing the joint between said enlarged end of the flue and the oven, and a counter balance for the flue, said flue and pipe being concentric with the axis of the opening.
9. The combination with a coke oven having a feed opening in the top thereof, of means for collecting generated gases, including a gas conducting pipe supported above the opening, a flue slidably mounted on said pipe, the lower end of said flue being adapted to rest upon the oven and to surround said opening, a packing ring extending around the pipe and supported by the flue, and a ring weight loosely mounted on the pipe and bearing on said packing ring to seal the joint between the pipe and flue.
10. The combination with an oven having a feed opening in the top thereof, of means for collecting generated gases, including a gas conducting pipe supported above the opening, a flue slidably mounted on said pipe, the lower end of the flue being adapted to rest on the oven and to extend around the opening, the upper end of the flue being flared, there being an annular shoulder upon the upper portion of said flue, packing rings upon the shoulder and flared end respectively of the flue, and a ring weight resting upon said rings to seal the joint between the ring and flue and between the flue and pipe.
11. The combination with a coke oven having a feed opening in the top thereof, of a gas collecting attachment including a ring insertible into the opening and having a grooved annular flange constituting a seat, a gas collecting pipe supported above the opening, a flue slidably mounted on the pipe and bearing at its lower end within the groove, means for sealing the joint between said flange and the flue.
12. The combination with a coke oven having a feed opening in the top thereof, of a gas collecting attachment including a ring insertible into the opening and having a grooved annular flange constituting a seat, a gas collecting pipe supported above the opening, a flue slidably mounted on the pipe and bearing at its lower end within the groove, means for sealing the joint between said flange and the flue, and means for sealing the joint between the flue and pipe.
13. The combination with a coke oven having a feed opening in the top thereof, of a gas collecting attachment including a ring insertible into the opening and having a grooved annular flange constituting a seat, a gas collecting pipe supported above the opening, a flue slidably mounted on the pipe and bearing at its lower end within the groove, means for sealing the joint between said flange and the flue, and means for sealing the joint between the flue and pipe, said flue having inwardly extended pressure receiving means.
14. The combination with an oven having a feed opening in the top thereof, of a gas collecting pipe supported above the opening, and a combined gas conducting flue and safety valve supported by the oven and extending around the opening, and slidably mounted on the pipe.
15. The combination with an oven having a feed opening in the top thereof, of a gas collecting pipe supported above the opening, a combined gas conducting flue and safety valve supported by the oven and extending around the opening, and slidably mounted on the pipe, and means for sealing the joint between the oven and the flue.
- In testimony that I claim the foregoing as my own, I have hereto affixed my signature in the presence of two witnesses.
